US00D447066B1

(12) **United States Design Patent** (10) Patent No.: **US D447,066 S**
Takayama et al. (45) Date of Patent: **** Aug. 28, 2001**

(54) **MEASUREMENT SURVEYING DEVICE**

943897-8 2/1999 (JP).
1081383 5/2000 (JP).

(75) Inventors: **Homu Takayama; Kenji Kaneko; Masayuki Ueno**, all of Tokyo (JP)

* cited by examiner

(73) Assignee: **Asahi Seimitsu Kabushiki Kaisha, Tokyo (JP)**

Primary Examiner—Antoine Duval Davis
(74) Attorney, Agent, or Firm—Sughrue, Mion, Zinn, Macpeak & Seas, PLLC

(**) Term: **14 Years**

(57) **CLAIM**

(21) Appl. No.: **29/131,305**

The ornamental design for a measurement surveying device, as shown and described.

(22) Filed: **Oct. 19, 2000**

DESCRIPTION

(30) **Foreign Application Priority Data**

FIG. 1 is a front elevational view of the measurement surveying device;

May 10, 2000 (JP) 12-012257

FIG. 2 is a rear elevational view thereof;

(51) LOC (7) Cl. **10-04**

FIG. 3 is a right side elevational view thereof;

(52) U.S. Cl. **D10/66**

FIG. 4 is a left side elevational view thereof;

(58) Field of Search D10/66; 33/290-299

FIG. 5 is a top plan view thereof;

(56) **References Cited**

FIG. 6 is a bottom plan view thereof;

U.S. PATENT DOCUMENTS

FIG. 7 is a partially-enlarged view of the rear elevational view;

D. 409,507 * 5/1999 Ishii D10/66

FIG. 8 is a partially-enlarged view of the right side elevational view;

D. 427,087 6/2000 Kaneko et al. .

FIG. 9 is a partially-enlarged view of the left side elevational view;

6,182,372 * 2/2001 Lamm 33/290

FIG. 10 is a partially-enlarged view of the top plan view;

FOREIGN PATENT DOCUMENTS

FIG. 11 is a perspective view of the measurement surveying device; and,

943897 10/1995 (JP) .

FIG. 12 is another perspective view of the measurement surveying device.

943897-2 4/1997 (JP) .

943897-3 5/1997 (JP) .

943897-4 5/1998 (JP) .

943897-5 6/1998 (JP) .

943897-6 2/1999 (JP) .

943897-7 2/1999 (JP) .
